TYPEWRITER RIBBON SPOOL COVER

James J. Bienkowski, Cazenovia, and Joseph A. Rauch,
Syracuse, N.Y., assignors to SCM Corporation, New
York, N.Y.

Filed Dec. 8, 1972, Ser. No. 313,205

Term of patent 14 years

Int. Cl. D18—01

U.S. Cl. D64—11 A

FIG. 1

FIG. 2

FIG. 3

FIG. 4

FIG. 5

FIG. 1 is a front perspective view of a typewriter ribbon spool cover showing our new design, the broken line illustration in this view only being for illustrative purposes to indicate environmental use;

FIG. 2 is a top plan view of the typewriter ribbon spool cover shown in FIG. 1;

FIG. 3 is a front elevational view;

FIG. 4 is a right side elevational view; and

FIG. 5 is a left side elevational view.

We claim:

The ornamental design for a typewriter ribbon spool cover, as shown.
